UNITED STATES PATENT OFFICE.

JOHN C. DUEBER, OF CANTON, OHIO.

DESIGN FOR A WATCH-DIAL.

SPECIFICATION forming part of Design No. 22,599, dated July 11, 1893.

Application filed March 14, 1893. Serial No. 465,974. Term of patent 14 years.

To all whom it may concern:

Be it known that I, JOHN C. DUEBER, a citizen of the United States, and a resident of Canton, county of Stark, State of Ohio, have 5 invented and produced a new and original Design for Watch-Dials, of which the following is a full, clear, and exact description, reference being had to the accompanying drawing, making part of this specification.

10 The figure of the drawing shows my new and original design, the same comprising the dial of a watch.

15 In the drawing the dial by means of dotted lines at right angles to each other is divided into four imaginary quadrants 1, 2, 3 and 4 respectively, No. 1, being that quadrant occupying the space between the character indicating twelve o'clock and that indicating three o'clock; No. 2, being that quadrant occupying 20 the space between the character indicating three o'clock and that indicating six

o'clock; No. 3, being that quadrant occupying the space between the character indicating six o'clock and that indicating nine o'clock; and, No. 4, being that quadrant occupying the space between the character indicating nine o'clock and that indicating twelve o'clock. Upon this dial and located upon the boundary between the first and second quadrants is placed the seconds circle *a*, partly upon the first quadrant, and partly upon the second quadrant, this being the characteristic or leading feature of this design.

What I claim is—

The design for watch dials herein shown 35 and described.

In testimony whereof I have hereunto set my hand this 4th day of March, A. D. 1893.

JOHN C. DUEBER.
